UNITED STATES PATENT OFFICE

2,397,808

PILE FABRIC FOR ABRASIVE BASE

Thomas Riding, Sanford, Maine, assignor to
Goodall-Sanford, Inc., Sanford, Maine, a corporation of Maine

Application November 8, 1944, Serial No. 562,456

2 Claims. (Cl. 139—401)

This invention presents a novel construction of pile fabric to form the base of an abrasive belt.

The pile fabric is designed to act as a matrix for, and to be coated on its face with, suitable abrasive material after the manner generally set forth in the patent to Colt et al. No. 2,347,244, April 25, 1944.

The object of the present invention is to provide such a pile fabric base which shall be practically non-stretchable in the direction of the warps so that when loaded with the abrasive and operated as a belt it will not stretch.

The object of the invention is further to provide a peculiar spacing of the pile tufts and a peculiar staggered relation thereof such that the abrasive when applied to the base fabric will be evenly distributed throughout the area of the pile face and so arranged that when the abrasive coated fabric is performing its intended function of an abrasive belt and is transversely curved progressively, as it passes around the supporting rolls, there will be no deleterious cracking and the abrasive will be presented uniformly and progressively to the work.

These and other objects and features of the invention will appear more fully from the accompanying description and drawing and will be particularly pointed out in the claims.

The drawing illustrates more or less diagrammatically and in opened-up form the pile fabric construction embodying the invention.

The invention makes use of a warp pile fabric of a generally familiar type in which the pile warps are formed into W's and as the method of and apparatus for weaving such pile fabrics are well known to those skilled in the art no further explanation thereof is necessary.

In the drawing:

Fig. 1 is a perspective view of a section of pile fabric embodying the invention much enlarged, with the elements widely spaced and with the proportions altered for purposes of illustration; and,

Fig. 2 is a diagrammatic top plan view of a section of the fabric for the purpose mainly of illustrating the arrangement of the pile tufts.

The fabric is made up of a set of pile warps, a set of slack warps, a set of non-stretchable ground warps, and a filling. The pile warps may be of suitable material and for that purpose a yarn composed wholly or in part of mohair has been found most satisfactory because of the inherent tendency of the mohair fibre, and thus the

pile tufts, to stand erect and straight from the ground.

The slack warps may also be made of any suitable material, but carded cotton yarn has been found most satisfactory. The ground warps constitute a vital feature of the fabric because it is upon them that the non-stretchable character of the fabric depends. These warps are preferably made of mercerized cotton. These ground warps are much finer than the slack warp and are stabilized and stretched in their formation as much as possible and during the weaving operation are maintained under as much tension as possible so that they weave and extend straight in the fabric. A plurality, four having been found desirable, of these ground warps weave as a single strand. The filling may also be made of any suitable material but preferably of a carded cotton yarn.

10 In the weave each slack warp weaves at one side of and sinuously with a pile warp and thus extends over and under successive filling picks, while a plurality of the non-stretchable ground warps extend as a single strand straight 15 at the other side of the weave and opposite to the pile warp under and over successive filling picks. The tension is so maintained during the weaving operation that the ground warps are maintained straight and act to cause the filling 20 picks or wefts, over which the slack and pile warps weave, to extend substantially straight in a plane above the ground warps and also to cause the filling picks or wefts, under which the slack and pile warps weave, to extend substantially 25 straight in a plane below the ground warps.

The principle of the weave will appear from Fig. 1 in which a series of dents of the weave are illustrated and numbered I, II, III, IV. In each dent is illustrated a slack warp 10, a series of 30 pile warp W's 11 each formed in the usual manner on three filling picks and having tufts 12 extending upright from the ground, and a series of four non-stretchable ground warps 13 forming a single strand. It will be seen now that the 35 construction is as already described, that is, throughout the width of the fabric a slack warp weaves at one side of and sinuously with a pile warp over and under the filling, while a strand composed of a plurality of the non-stretchable ground warps weaves at the other side of the pile warp and opposite thereto, that the ground warps extend straight throughout the fabric, and that the filling picks 2, 4, 6, and 8, over which the slack and pile warps bend, extend themselves straight and in a plane above the ground warps,

while the filling picks 1, 3, 5, and 7, under which the slack and pile warps bend, extend themselves straight and in a plane below the ground warps.

In a particular construction of fabric found highly satisfactory the filling is of 7/1 carded cotton yarn, the slack warps are 20/2 carded cotton yarn, the tight warps 20/2 mercerized cotton yarn, and the pile warps 2/20 mohair.

When the fabric is beaten up into its finished form in weaving the plurality of ground warps crowd together to form a compact strand and the effect at the back of the fabric is that of single alternating slack and ground warp strands of about the same size.

The finished fabric is preferably given a light coating on the back of the ground of a suitable adhesive of rubber, pyroxylin or other material such as is employed for that purpose.

An important feature of the fabric is the arrangement of the pile tufts such that, when the fabric is loaded or coated with the abrasive material, this abrasive material shall be evenly distributed throughout the surface. The projecting tufts and the spaces between the tufts covered with the abrasive material present an even uniform abrasive action when the fabric is acting as an abrasive belt and is progressively curved transversely in bending at its supporting wheels. Thus there is no deleterious cracking or opening up of the abrasive or breaking and injury of the fabric base. This result is secured by the construction illustrated in perspective in Fig. 1 and diagrammatically in plan in Fig. 2. In Fig. 2 the filling picks are indicated and numbered 1-8 and the longitudinal rows of pile tufts as they occur in each dent are indicated by the numbers I, II, III, IV. The tufts 12 of each W-11 in this Fig. 2 are indicated as black disks. The arrangement is that each pile warp forms a W on three filling picks of each group of eight picks and that the centers of the W's of the first, second, third and fourth pile warps in each repeat of four successive pile warps respectively overlie the sixth, second, eighth and fourth pick of each eight pick repeat, that is, in row I the centers of the W's extend over the sixth pick in each group of eight, in row II over the second pick of each group of eight, in row III over the eighth pick of each group of eight, and in row IV over the fourth pick of each group of eight. Thus the pile tufts in successive transverse rows present a peculiar staggered relation and insure, as the fabric progressively advances in a longitudinal direction, that there shall be an even and regular abrasive action.

The construction of the fabric in accordance with this invention by reason of the arrangement of the filling and the ground warps insures that the tufts of pile at each end of the W shall stand up vertically chiefly because the picks of filling in the upper plane press against the outside of the tufts.

While the abrasive may crack slightly in different places and for short distances, the construction of the fabric is such that any such cracks are not regular transverse extensive cracks, nor is the fabric, heavily stiffened by the

abrasive, itself cracked, injured or broken as it passes around the belt-supporting wheels. Thus there is no deleterious transverse cracking.

The fabric, particularly by reason of the non-stretchable ground warps and also by the straight extension of the filling picks or wefts, is practically non-stretchable and thus presents a highly effective base for an abrasive belt. While this characteristic is essentially due to the weave structure it is desirable that in all treatment and handling of the fabric until it is finished and coated with the abrasive the fabric shall be kept stretched longitudinally.

There is thus presented a novel, practical and highly effective non-stretchable warp pile fabric to form the base of an abrasive belt.

Having thus described the invention, what is claimed as new and desired to be secured by Letters Patent is:

1. A longitudinally non-stretchable warp pile fabric constructed to carry abrasive material without deleterious transverse cracking when curved transversely and to present the pile tufts of successive transverse rows in staggered relation consisting of a set of pile warps, a set of slack warps, a set of ground warp strands each composed of a plurality of non-stretchable ground warps, and a filling, in which each pile warp forms W's on three filling picks of each repeat of eight picks with the centers of the W's of the first, second, third and fourth pile warps in each repeat of four successive pile warps bent over respectively the sixth, second, eighth, and fourth pick of each eight pick repeat in which a slack warp weaves at one side of and sinuously with each pile warp over and under successive filling picks, and in which a ground warp strand composed of a plurality of the non-stretchable ground warps extends straight in the fabric weaving at the other side of and opposite to each pile warp under and over successive filling picks.

2. A longitudinally non-stretchable warp pile fabric constructed to carry abrasive material without deleterious transverse cracking when curved transversely and to present the pile tufts of successive transverse rows in staggered relation consisting of a set of pile warps, a set of slack warps, a set of ground warp strands each composed of a plurality of non-stretchable ground warps relatively small as compared with the slack warps, and a filling, in which each pile warp forms W's on three filling picks of each repeat of eight picks with the pile tufts in successive transverse rows presenting a staggered relation, in which a slack warp weaves at one side of and sinuously with each pile warp over and under successive filling picks, and in which a ground warp strand composed of a plurality of the non-stretchable ground warps extends straight in the fabric weaving at the other side of and opposite to each pile warp under and over successive filling picks and with the non-stretchable ground warps crowded together in each strand to form a compact strand giving the effect on the back of the ground of the finished fabric of alternating slack and ground warp strands.

THOMAS RIDING.
